UNITED STATES PATENT OFFICE.

JAMES D. FRARY, OF NEW BRITAIN, CONNECTICUT.

DESIGN FOR HANDLE FOR TABLE-CUTLERY.

Specification forming part of Design No. 7,078, dated December 30, 1873; application filed December 17, 1873.
[Term of Patent 7 years.]

B.

To all whom it may concern:

Be it known that I, JAMES D. FRARY, of New Britain, in the county of Hartford and State of Connecticut, have invented a new Design for Handle for Table-Cutlery; and I do hereby declare the following, when taken in connection with the accompanying drawing and the letters of reference marked thereon, to be a full, clear, and exact description of the same, and which said drawing constitutes part of this specification, and represents a side view of a table-knife.

This invention relates to a design for the handles of table-cutlery, illustrated in a knife, but applicable to other articles of table-cutlery; and it consists in the peculiar form of the bolster and tip, together or separately.

A is the tip; B, the bolster. On the surface of these is a four-sided figure, as denoted in

solid black, two of the angles being in nearly a longitudinal line of the handle; the other two transverse, or nearly so, at right angles across the handle. The outline of the tip and bolster constitutes no part of this design.

In some cases the bolster only is used, and in others the tip only, with a bolster of different construction. I do not, therefore, confine myself to the combination of the tip and bolster, but either together or separately.

I claim as my invention—

The design for cutlery-handle, as herein described, and shown in the accompanying illustration.

JAMES D. FRARY.
